UNITED STATES PATENT OFFICE.

BRUNO MÜLLER, OF ZWENKAU, SAXONY, GERMANY.

COOLER FOR MILK.

SPECIFICATION forming part of Letters Patent No. 249,386, dated November 8, 1881.
Application filed April 23, 1881. (No model.)

To all whom it may concern:

Be it known that I, BRUNO MÜLLER, of the city of Zwenkau, in Saxony, German Empire, have invented a new and Improved Cooler for Milk or other Fluids, of which the following is a specification.

This invention consists in the construction of a cooling apparatus for fluids, capable of having the space between the cooling-surfaces increased or diminished, as may be desired, and which can be readily taken apart for the purpose of cleaning, which latter circumstance is particularly of great consequence if the apparatus is employed for cooling milk.

In the accompanying drawings, Figure 1 represents an outside elevation of my cooling apparatus. Fig. 2 is a vertical section of the same. Fig. 3 is a plan or top view. Fig. 4 is a vertical section of the cooling-chambers, and Figs. 5 and 6 are details.

Similar letters represent similar parts in all the figures.

A A' are flat hollow cooling-chambers of any desired width, bent in a zigzag shape, as shown in Fig. 2, fitted between side plates, G G', against which a tight joint is made by means of india-rubber or any other suitable packing, and fastened together through bolts l l. The water or other cooling medium is introduced into the interior of these chambers A and A' through pipes n n', and escapes through pipes m m', or vice versa. To cause this water or cooling medium to circulate in a horizontal direction plates or partitions g g are arranged in the corners where the chamber-plates are bent, and arranged alternately on one or the other side, as shown in Fig. 4. By this arrangement the sides of the chambers A A' are braced, and at the same time strengthened. The chamber A' is made stationary, and the chamber A is at

its upper end provided with a cross-bar, d, resting upon the frame F, and at its lower end with suitable feet, d', resting upon the cross-piece F'. The ends of the bar d and of the feet d' are made with slots e, through which the bolt f passes, provided with a suitable nut, h. (See Figs. 5 and 6.) By this arrangement the cooling-chamber A can easily be moved outward or inward, so as to increase or diminish the space B between the surfaces of the coolers A and A', as may be desired, or said chamber A can readily be removed altogether for the purpose of cleaning the inner surfaces or space, B.

The milk or other fluid to be cooled is collected in the reservoir C and passes through the faucet a into the trough D, provided with perforations i in its bottom, and thus runs into the space E in the upper end between the cooler-chambers A A', and then passes the inclined surfaces of the coolers in a thick or thin body, according to the position of these coolers A A' from each other. After passing through the apparatus the milk or other fluid runs into the trough b, and then into the reservoir H, or it may be conducted through pipes to any desired place.

What I claim as my invention, and desire to secure by Letters Patent, is—

The stationary zigzag-shaped cooling-chamber A', with the movable zigzag cooling-chamber A, provided with a cross-bar, d, at top and feet d' d' at bottom, in combination with the side plates, G' G', suitable end packing, and bolts l l, arranged and constructed to operate in the manner and for the purpose described.

BRUNO MÜLLER.
